FIG. 1 is a rear elevational view of a garage door showing my design;

FIG. 2 is an enlarged front elevational view of FIG. 1, broken away for ease of illustration;

FIG. 3 is a top plan view of FIG. 1;

FIG. 4 is an enlarged side elevational view taken from the right side of FIG. 2, rotated 90° clockwise, the left side being a mirror image thereof;

FIG. 5 is an enlarged sectional view taken on line 5—5 of FIG. 2, rotated 90° clockwise;

FIG. 6 is a front elevational view of a modified garage door which is identical to the design of FIGS. 1-5 except that the adjacent panels are rigidly connected rather than hingedly connected and there are no windows, FIG. 6 being broken away for ease of illustration; and

FIG. 7 is an enlarged perspective view of FIG. 6 with the edge in longitudinal cross-section.

I claim:

The ornamental design for a garage door, as shown and described.
